UNITED STATES PATENT OFFICE.

VINCENT GEHRLEIN, OF ERIE, PENNSYLVANIA, ASSIGNOR TO LOVELL MANUFACTURING COMPANY, OF ERIE, PENNSYLVANIA, A CORPORATION OF PENNSYLVANIA.

WRINGER.

Application filed October 13, 1926. Serial No. 141,279.

This invention is particularly directed to the construction or mounting of a rest plate and provides a simple and efficient construction of plate permitting the use of comparatively light material and a construction which may be readily assembled. Features and details of the invention will appear from the specification and claims.

The invention is illustrated in the accompanying drawings as follows:—

Fig. 1 shows a side elevation of the wringer.

Fig. 2 a front view.

Fig. 3 an enlarged perspective view of one of the connections of the rest plate.

1—1 mark the side stiles of the frame, 1^a the top bar, 1^b the bottom bar, 2—2 the wringer rolls mounted in the side stiles, and 3 guards at the ends of the wringer rolls.

20 The guards are preferably made of sheet metal and are mounted in the usual manner in the side stiles.

The guards have the side faces 4 with the flanges 5 extending over the face of the rolls 25 as is the usual construction. A pintle 6 is struck up in the face 4, the pintles of the guards extending outwardly.

A rest plate 7 is formed of thin metal flanged at 8 and has its ends bent at 9 and 30 these ends have perforations 10.

In assembling the ends 9 are sprung apart sufficiently to permit the perforations to snap into place over the pintles 6. By arranging the pintles with an outward direc-

tion and spreading the ends 9 in assembling them the connection is secure because any added strain placed upon the rest plate tends to draw the ends 9 together, or more securely into engagement with the faces of the guards and more securely on the pintles. Further 40 the outwardly deflected pintles can be readily formed in relation to the stamping of the guard plate in that in striking them up the movement of the dies is in the same direction as in the forming of the flanges 5. 45

What I claim as new is:—

1. In a wringer, the combination of side stiles; rolls mounted therein; metal guard plates at each end of the rolls having outwardly extending pintles; and a rest plate 50 having resilient ends extending at an angle to the rest plate and in approximately parallel relation, said ends having perforations through which the pintles extend.

2. In a wringer, the combination of side stiles; rolls mounted therein; metal guard plates at each end of the rolls having flanges struck up thereon overlapping the face of the rolls and outwardly extending pintles struck up from the metal of the guard plate; 60 and a rest plate having resilient ends extending at an angle to the rest plate and in approximately parallel relation, said ends having perforations through which the pintles extend. 65

In testimony whereof I have hereunto set my hand.

VINCENT GEHRLEIN.
